ABSTRACT

The purpose of the invention is to provide a system for using normal and high pitched roofs for buildings preassembled in box-like units at a factory and transported to the building site over the highway or other means, wherein low road clearances and other restrictions prohibit the use of assembled units exceeding a certain height and width. The invention permits the roof, which otherwise would exceed the height limitation, to be unfolded after delivery at the building site in such a manner that it will assume the desired position with a minimum of site labor. The system is not limited to any particular structural, roof deck, or roofing material nor to a building of any particular size or number of stories.

**COLLAPSIBLE ROOF FOR PREASSEMBLED
BUILDING**

This application is related to my prior patent "Collapsible Roof for Preassembled Building," Ser. No. 846,551, filed July 31, 1969, and granted Feb. 1, 1972, U.S. Pat. No. 3,638,373.

The invention will be further described with reference to the attached drawings wherein:

FIG. 1 is an isometric birdseye view showing the roof unfolded and raised over two box-like units and gables filled in;

FIG. 2 is a section showing the building with the roof raised;

FIG. 3 is a half section of the roof in position prior to unfolding;

FIG. 4 is a half section of the roof after the first step of unfolding;

FIG. 5 is a half section of the roof after the second step of unfolding;

FIG. 6 is half section of the roof after the final step of unfolding;

FIG. 7 is detail of the eave in final position;

FIG. 8 is a detail of the purlin member;

FIG. 9 is a detail of an alternate purlin arrangement.

FIG. 2 is a section through the completed building illustrated in FIG. 1. The left hand half represents one factory assembled box with its roof unfolded at the site. The dotted right hand half shows the eventual position of the other half of the building. FIGS. 2 and 3 show optional upright *m* being used for support of the roof during transportation.

Labelled on FIG. 2 are the principal structural components of each frame or truss supporting half the roof, each of which will be sized and spaced according to engineering practice. The members are described as follows:

a. Lower portion of rafter or truss compression member covered with roof deck and roofing.

b. Opposing chord compression member.

c. Upper portion of rafter similar to *a*, supporting ridgepole at *i*.

d. Temporary support spaced as required to support half the roof until it has been connected permanently to the other half of the roof shown dotted on FIG. 2.

e. Stop, applied to bottom of member *a*.

f. Ceiling joist or tension chord of the truss.

Dotted line *c'* shows an alternate double slope roof design which can be produced by the same invention.

The following procedure will be used to unfold the roof and raise it into position (see FIGS. 3 through 6).

Step 1: (See FIG. 3) Slide folded roof, members *a* and *c*, until stop *e* rests against plate *j* as in FIGS. 4 and 7.

Step 2: (See FIG. 4) Hook grapple around purlin *l* and hoist until members *b* fall into place as in FIG. 5 and is secured at point *k*.

Step 3: (See FIG. 5) Hoist member *c* by grappling ridge member *i*, rotate it about hinge *h* and lower it into position shown on FIG. 6, and temporarily support it with member *d* as in FIG. 6.

Steps 4, 5, and 6: Follow the same procedure for the

other half of roof at right of FIG. 2, so that members *c* of both halves are mutually supporting.

Step 7: FIG. 7 is a detail at the roof eave after completion of Step 2 showing how stop *e* comes to rest on plate *j*, automatically locate rafter *a* at the correct position relative to the box unit below. Straps *g* are shipped already bolted to the ceiling joists *f*, and after unfolding of the roof are secured to each rafter *a*.

FIG. 8 shows transverse purlin member *l* which incorporates a ledge upon which member *b* falls into place and rests after member *a* is raised from position FIG. 4 to position FIG. 5. It also details hinge *h* about which upper rafter *c* rotates during the third and final step of unfolding the roof. All roofing material will be applied at the factory, except over the fold at the hinge, which will be applied at the erection site (shown dotted).

FIG. 9 is a detail of an alternate roof form of which the invention is capable and also shows an alternate hinge which will permit installing the entire roofing surface at the factory, with flashing used to seal the step in the roof.

I claim:

1. A preassembled building having a collapsible roof comprising:

- a. A pair of box-like structures each structure having a floor, a vertical outer wall, a vertical inner wall and a ceiling joist;
- b. Said box-like structures abutting at said inner walls;
- c. Above each box-like structure a collapsible roof comprising a roof deck and roofing attached thereto;
- d. Said roof deck attached to a plurality of parallel folding trusses each truss consisting of an upper and lower rafter member;
- e. Spaced inwardly from the lower end of the lower rafter an angled indentation;
- f. Adjacent the inner edge of said indentation a protruding stop;
- g. At the outer edge of said ceiling joist a rest plate;
- h. Said rest plate, indentation and stop cooperating to attach said lower rafter member to said outer edge of said ceiling joist;
- i. The upper end of the lower rafter and the lower end of the upper rafter rotatably attached at a purlin;
- j. The upper end of the upper rafter terminating at a ridge member at the top, and abutting the corresponding upper rafter of the opposite box-like structure;
- k. An interlocking compression member, the lower end of the member attached adjacent the inner wall of the box below;
- l. The upper end of the compression member supporting the rafters at the purlin; whereby during transit said roofing structure is collapsed onto said ceiling joist.
2. The structure of claim 1 wherein said upper rafter is steeper than said lower compression truss rafter thus making a roof of increased height and pitch.
